UNITED STATES PATENT OFFICE.

PAUL RAFALOVITZ, OF NEW YORK, N. Y.

DESIGN FOR A GAME-BOARD.

SPECIFICATION forming part of Design No. 25,624, dated June 9, 1896.

Application filed October 7, 1895. Serial No. 564,953. Term of patent 3½ years.

To all whom it may concern:

Be it known that I, PAUL RAFALOVITZ, a citizen of the United States, and a resident of New York, in the county of New York and State of New York, have invented and produced a new and original Design for Game-Boards, of which the following is a specification, reference being had to the accompanying drawings, in which—

10 Figure 1 is a plan view of my new and original design for a game-board, and Fig. 2 a cross-section of the same on line 2 2 of Fig. 1.

The leading feature of my design comprises a bottom board or plate A, rectangular in 15 form, and from which projects an upwardly-directed rim or flange provided with a cover, and formed on the surface of the bottom board or plate are a series of figures D, E, F, G, and H, which are in regular contour and designed 20 to represent the grand division of the earth's surface, and formed within the line which

bounds said figures is a circular recess or cavity K.

My new and original design is limited to a box or case, the vertical sides and end 25 bounds, the figures or representations, which are colored and formed on the bottom of the box, and a circular cavity or recess formed in each of said figures or representations.

Having fully described my invention, I 30 claim and desire to secure by Letters Patent—

The design for a game-board, substantially as herein shown and described.

In testimony that I claim the foregoing as 35 my invention I have signed my name, in presence of the subscribing witnesses, this 4th day of October, 1895.

PAUL RAFALOVITZ.
